CLAIM

The ornamental design for a stock for a submachine gun, as shown and described.

DESCRIPTION

FIG. 1 is a left elevation view of a stock for a submachine gun showing the design;

FIG. 2 is a right elevation view thereof;

FIG. 3 is a rear elevation view thereof;

FIG. 4 is a top plan view thereof;

FIG. 5 is a bottom plan view thereof;

FIG. 6 is a rear perspective view thereof;

FIG. 7 is a left elevation view thereof, shown in an alternate position;

FIG. 8 is a right elevation view thereof, shown in the alternate position;

FIG. 9 is a rear elevation view thereof, shown in the alternate position;

FIG. 10 is a front elevation view thereof, shown in the alternate position;

FIG. 11 is a top plan view thereof, shown in the alternate position;

FIG. 12 is a bottom plan view thereof, shown in the alternate position; and,

FIG. 13 is a rear perspective view thereof, shown in the alternate position.

A front elevation view has been omitted from the first illustrated position as it does not form a portion of the
